UNITED STATES PATENT OFFICE.

LEWIS W. SCUTT, OF ST. LOUIS, MISSOURI.

DEVICE FOR TEACHING TIME IN MUSIC.

Application filed October 24, 1925. Serial No. 64,488.

This invention relates to improvements in device for teaching time in music and consists of the novel construction hereinafter disclosed.

- 5 An object of the invention is to provide a device including a support and a plate carried by the support in which there is formed slots restricting the movement of a baton or time-beating device, said slots being 10 arranged so that the time values of notes may be definitely indicated in combination with a metronome for coordinating the movement of the time-beating device within the slots.
- 15 The specific advantages of the invention will appear from the following detailed description thereof, taken in connection with the accompanying drawing in which,

- 20 Fig. 1 is a plan view;
 Fig. 2 is a front elevation;
 Fig. 3 is an end elevation;
 Fig. 4 is a cross section on the line 4—4 of Fig. 2; and

- 25 Fig. 5 is a detail view of the settable devices for subdividing the slots for time indication.

In the embodiment of the invention illustrated in the drawing, the device is shown as including a base 1 and a standard or support 30 including an angular strap having arms 2, 3 and 4. The arm 2 is movably secured to the base 1 by a bolt 5 and a wing nut 6. The arm 4 extends in a horizontal direction and has a slot 7 formed therein, the said slot extending inwardly from one side edge of the arm. A pendulum arm 8 having a weight 9 secured thereto carries a clip 10 having vertically extending arms 11, the lower edges of which are beveled to form 35 a knife edge that rests on the arm 4 over the marginal edges of the slot 7, thereby supporting the pendulum arm for rocking movement.

40 A guard in the form of a U-shaped plate 45 12 is pivoted to the arm 4 at 13 and is adapted to swing inwardly to prevent the pendulum arm from moving out of the slot 7. The pendulum arm below the arm 4 is provided with a clip 14 that has lateral wings 15, said wings constituting stop devices to limit the throw of the pendulum arm.

45 In order to control the rate of swing of the pendulum arm, the upper part thereof is provided with a weight 16 that is adapted

to be set at different vertical adjustments on the arm to control the speed of oscillation thereof according to the setting of the weight, which setting is controlled by a scale 17 on the face of the pendulum arm. 60

Supported transversely of the arm 3 is a plate 18 having formed therein two vertical slots 19 and 20. The slot 19 is graduated to indicate subdivisions of a beat in time marked C, 2/4, 3/4 and 4/4, and the slot 20 is subdivided for time marked 3/8, 6/8, 9/8 and 12/8. For example, and referring to slot 19, the movement from top to bottom of the slot in a time indicated by a complete oscillation of the pendulum arm would be 70 the value of a quarter note for the times indicated. In other words, the operator of the device would insert a baton in the slot 19 and by coordinating the movement of the baton with the movement of the pendulum arm, that is, lowering the baton from the top of the slot to the lower part of the slot during the movement of the pendulum arm in one direction and from the bottom of the slot to the top during the movement 80 of the arm of the pendulum in the other direction, the operator would have indicated the value of a quarter note. Obviously two movements from top to bottom of the slot would indicate the value of a half note and four movements would indicate the value of a whole note. Similarly, the movement from top to bottom or from bottom to top would be the value of an eighth note, a half movement in a vertical direction in the slot would be a sixteenth note, a fourth movement a thirty-second note, and an eighth movement a sixty-fourth note. Thus the entire range 90 of note values may be indicated by the movement of the baton in the slot. 95

In order to subdivide the slot for the values under the value of a quarter note, there are provided clips 21 which frictionally engage over the edge of the slot and project a slight distance beyond the edge of the slot so that in traversing the edge of the slot with the baton, the operator will cause the baton to come into contact with the clip and by both the sense of touch and the sound made from the baton coming into contact with the clip, the lapse of time corresponding to the value of the particular note indicated will be observed.

For instance, in the illustration of Fig. 2, the clip is shown midway of the slot on one 110

side so that when the baton has moved from the graduation mark 1, to the graduation mark 3 in the time indicated by the movement of the pendulum arm, the value of a sixteenth note will have been indicated. Similarly, it will be understood that the value of dotted notes may be indicated as for example the movement from the graduation mark 3 around the edge of the slot to the graduation mark 1 would indicate the value of a dotted eighth note.

By reference to the graduations on the slot marked 20 it will be noted that the slot is so subdivided as to mark the value of the notes in triple time, the settings and the values being obvious from the description in relation to the settings and graduations of the slot 19 provided for double time.

The device has the advantage of teaching musical time and rhythm both by the sense of hearing and by the sense of touch and by its use, the pupil may be taught the accurate subdivision of note values and the values may be accurately demonstrated. By using the device for practicing the beating of time, the pupil acquires a definite knowledge of note values and will be enabled to acquire an accurate musical sense of values in playing musical instruments. It is intended that the instruction in time and rhythm by use of the device disclosed shall be carried on as independent instruction, it having been found in practice that if a pupil acquires a definite sense of time, it may be readily put in practice in playing musical instruments.

From the foregoing description it will be

understood that the device of the invention attains the results desired. It will also be understood that it may be modified in structure without departing from the spirit and scope of the invention and

What I claim and desire to secure by Letters Patent is:

1. A device for teaching time in music including a plate having an elongated slot formed therein to indicate time value, said slot being provided with graduations for subdividing it into time values, and adjustable devices settable on said graduations for indicating the subdivision of time values.

2. A device for teaching time in music including a plate having an elongated slot formed therein to indicate the time values, said slot being provided with graduations for subdividing it into time values, adjustable devices settable on said graduations for indicating the subdivisions, and a metronome device for synchronizing the time value with the time value indicated by the slot.

3. A device for teaching time in music including a plate having an elongated slot formed therein to indicate the time values, said slot being provided with graduations for subdividing it into time values, adjustable devices settable on said graduations for indicating the subdivisions, a metronome device for synchronizing the time value with the time value indicated by the slot, and means for adjusting the tempo of the metronome device.

LEWIS W. SCUTT.
